UNITED STATES PATENT OFFICE.

LEWIS M. HULL, OF BOONTON, NEW JERSEY, ASSIGNOR TO RADIO FREQUENCY LABORATORIES INCORPORATED, OF BOONTON, NEW JERSEY, A CORPORATION OF NEW JERSEY.

AMPLIFIER CIRCUIT.

Application filed November 17, 1926. Serial No. 148,975.

This invention relates to an electrical amplifier circuit for use in association with a four-electric vacuum tube of the type having an emitting cathode, an anode, and two grid electrodes. For many purposes it is desirable to operate such a vacuum tube according to a method, known in this art, which includes employing the grid G_1 , which is next the cathode, or which is the inner grid in a concentric arrangement, as the control element, and giving to the grid G_2 , which is next the anode, a positive bias. This method of operating a four-electrode tube makes use of what may, for convenience, be termed the "emission-shield" effect of the grid G_2 . The result is an increase in the effective alternating current plate impedance of the tube, due to the fact that the effect of the plate voltage upon the total electric field attracting the space current to the plate is greatly reduced by the shielding action of the grid G_2 . Another effect is the reduction of the effective interelectrode tube capacity between the control grid G_1 and the plate, and a consequent reduction of undesirable retroactive currents which are fed back from the output circuit to the input circuit, through these tube capacities.

This method of operating a four-electrode vacuum tube as an electrical amplifier does not, in many instances, accomplish of itself a sufficient suppression of these undesirable currents. This invention relates to means for reducing or suppressing these undesirable feed-back currents in a four-electrode vacuum tube when operated as an electrical amplifier in the manner described.

I have found that by impressing upon the grid, G_2 , a voltage having the proper amplitude and phase relation, as will be later explained, to the voltage of the control grid G_1 , I can reduce to any desired extent, or suppress, the undesirable feed-back currents which otherwise flow through the tube capacities.

This may be accomplished in various ways, certain typical ones of which I will now describe in connection with the accompanying drawings.

Figures 1, 2, 3 and 4 are diagrams illustrating certain specific embodiments of my invention.

Fig. 1 shows a four-electrode vacuum tube having emitting-cathode F , anode P , (control) grid G_1 , a second (emission-shield)

grid G_2 , and input and output circuits C_1-L_1 , and C_2-L_2 , respectively. The input and output circuits may be tuned or not as desired. They are here shown as being tuned, but in the case of a cascaded amplifier having two or more stages I may use, for example, transformer coupling between the stages, and may tune only the transformer secondaries. This is shown in Fig. 4. In a cascade arrangement, direct or other coupling may equally be used. The input or output circuits may be untuned, whether the audions are cascaded or not. The "A", "B", and "C" batteries are arranged as usual. The grid, G_2 , is connected to the filament through coil L_3 , which is coupled to coil L_1 in the input circuit. The proper positive bias is imparted to the grid G_2 , by including more or less of the "B" battery in this lead, or otherwise.

In this case coil L_3 should be so wound with respect to L_1 , that the compensating voltage impressed upon G_2 is opposite in phase to the voltage on the grid G_1 . The amplitude of the compensating voltage may be adjusted to give the desired suppression of the feed-back currents. This may be done by giving L_3 and L_1 the proper coupling or in other ways. Various values of the coupling coefficient between these coils are suitable; I have used a coefficient of coupling equal to .5 with satisfactory results. The operation of my circuit is not dependent upon the use of substantially unity coupling between these coils, as is the case with certain other circuits, for example that known as the neutrodyne. In some instances I find it advantageous to employ capacity C_2 , connected between the grid G_2 and the plate, as in Figures 1, 3 and 4, or between the grids G_1 and G_2 , as in Fig. 2.

An arrangement like that shown in Fig. 1 produces other beneficial results in addition to the suppression of feed-back currents. An important advantage arises from the secondary control effect exerted by the grid G_2 , in virtue of the coupling between coils L_1 and L_3 . This control effect is of such a nature that more constant amplification is obtained over a range of wavelengths.

In Fig. 2 the compensating voltage is applied to the grid G_2 by means of coil L_3 coupled to coil L_2 of the output circuit. The coil L_3 should be so wound with respect to L_2 that the voltage upon G_2 is in phase with the

voltage upon G_1 at resonance; that is, the voltage upon G_2 is opposite in phase to the voltage upon the anode, P . The remainder of the circuit may appropriately be arranged as before.

In this arrangement, in addition to the suppression of feed-back currents, the secondary control effect of grid G^2 tends to increase the amplification of the vacuum tube.

10 Fig. 3 shows an arrangement for applying the compensating voltage to the grid G_2 by means of coil L_3 in series with coil L_1 of the input circuit, but not necessarily coupled thereto. A by-pass condenser C^1 is then 15 employed, and the tuning condenser C_1 may be connected across both coils L_1 and L_3 as shown.

Fig. 4 has already been referred to in describing Fig. 1. It shows one suitable method of cascading a plurality of vacuum tube amplifiers arranged according to this invention. The circuit of Fig. 1 is here illustrated in cascade by way of example only. The circuits as shown in the other figures may also 25 be cascaded.

The circuits herein shown are of course merely typical of the means which I have found by experiment to be appropriate for carrying out my invention, by impressing 30 the proper compensating voltage upon the grid G_2 . Equivalent circuits for accomplishing this result, or variations of the circuits shown, fall within my invention.

I claim:

35 1. An electrical amplifier comprising a vacuum tube having an emitting cathode, an anode, a control grid, and a second grid, an input circuit connected between said cathode and said control grid, an output 40 circuit connected between said cathode and said anode, and means associated with one of said circuits for impressing upon said second grid a compensating voltage of the proper phase and amplitude to oppose feed-back currents flowing through the capacities of said vacuum tube between said anode and said control grid.

45 2. An electric amplifier comprising a vacuum tube having an emitting cathode, an anode, a control grid, and a second grid, an input circuit connected between said cathode and said control grid, an output circuit connected between said cathode and said anode,

and a coil connected between said cathode and said second grid, and coupled to a coil 55 in one of said circuits in such a way as to impress upon said second grid a compensating voltage of the proper phase and amplitude to oppose feed-back currents flowing through the capacities of said vacuum tube 60 between said anode and said control grid.

3. An electric amplifier comprising a vacuum tube having an emitting cathode, an anode, a control grid, and a second grid, an input circuit connected between said cathode and said control grid, an output circuit connected between said cathode and said anode, and a coil connected between said cathode and said second grid and coupled to a coil 65 in said input circuit in such a way as to impress upon said second grid a compensating voltage of the proper phase and amplitude to oppose feed-back currents flowing through the capacities of said vacuum tube 70 between said anode and said control grid. 75

4. An electric amplifier comprising a vacuum tube having an emitting cathode, an anode, a control grid, and a second grid, an input circuit connected between said cathode and said control grid, an output circuit 80 connected between said cathode and said anode, and a coil connected between said cathode and said second grid and so coupled to a coil in said input circuit as to impress a compensating voltage upon said second grid to oppose feed-back currents flowing through the capacities of said vacuum tube between said anode and said control grid. 85

5. An electric amplifier comprising a 90 vacuum tube having an emitting cathode, an anode, a control grid, and a second grid, an input circuit connected between said cathode and said control grid, an output circuit connected between said cathode and said anode, a coil connected between said cathode and said second grid and so coupled to a coil in 95 said input circuit as to impress upon said second grid a compensating voltage to oppose feed-back currents flowing through the 100 capacities of said vacuum tube, and a capacity connected between said second grid and said anode.

In testimony whereof, I affix my signature.

LEWIS M. HULL.
